CLAIM

The ornamental design for a baking and cookie sheet, as shown and described.

DESCRIPTION

FIG. 1 is a perspective view of a baking and cookie sheet,
showing our new design;

FIG. 2 is a top plan view thereof;

FIG. 3 is a side elevational view of one side thereof;

FIG. 4 is a bottom plan view thereof;

FIG. 5 is a side elevational view of the other side thereof.

FIG. 6 is a front elevational view thereof; and,

FIG. 7 is a rear elevational view thereof.
